Primary Examiner — Michael A Pratt(74) *Attorney, Agent, or Firm* — Oppedahl Patent Law Firm LLC(57) **CLAIM**

The ornamental design for a hubcap for a wheel, as shown and described.

DESCRIPTION

Figure 1.1 is a front view of a hubcap for a wheel showing our new design;

Figure 1.2 is a back view thereof;

Figure 1.3 is a left side view thereof;

Figure 1.4 is a right side view thereof;

Figure 1.5 is a top view thereof;

Figure 1.6 is a bottom view thereof; and

Figure 1.7 is a front-right perspective view thereof.

The broken lines in Figure 1.2 are included for the purpose of illustrating a portion of the hubcap that forms no part of the claimed design.

1 Claim, 7 Drawing Sheets(56)
